UNITED STATES PATENT OFFICE.

ALBERT M. MOTT, OF HAMPTON, IOWA.

AUTOMATIC ELECTRIC BLOCK SYSTEM.

No. 813,909.

Specification of Letters Patent.

Patented Feb. 27, 1906.

Application filed June 26, 1905. Serial No. 267,160.

To all whom it may concern:

Be it known that I, ALBERT MONROE MOTT, a citizen of the United States of America, residing at Hampton, in the county 5 of Franklin and State of Iowa, have invented certain new and useful Improvements in Automatic Electric Block Systems, of which the following is a specification.

This invention relates to electric signals for 10 railroads, and is designed to indicate the presence or non-presence of a train upon any particular portion of the railroad-track, said portion usually being termed a "block."

An object of the invention is to arrange the 15 wiring, lights, and other apparatus to indicate by electric signals at each end of the block and also, if desired, at stations along or contiguous to the block the presence or absence of trains within the block.

Furthermore, an object of this invention is 20 to provide a novel signal of this kind whereby a switch for controlling the signal is positively operated and to employ a main feed-wire for the circuit in combination with two 25 branch wires, said main wire operating alternately with the branches to complete the circuit to operate the signal, the branch wires or lines being supplied with lights at each end of the block. Said branch wires may be also 30 carried within the stations along the block and be provided with additional lights therein to act in conjunction with the end lights.

Finally, an object of the invention is to provide a device of the character noted possessing 35 advantages in points of simplicity, efficiency, and durability, proving at the same time comparatively inexpensive to produce and maintain.

With the foregoing and other objects in 40 view the invention consists in the details of construction and in the arrangement and combination of parts to be hereinafter more fully set forth and claimed.

In describing the invention in detail reference will be had to the accompanying drawings, forming part of this specification, wherein like characters denote corresponding parts in the several views, in which—

Figure 1 is a view in elevation of a section 50 of a road-bed, showing the operating-switches for the signals, a section of a locomotive illustrating the means for operating the

switches. Fig. 2 is a sectional view of the switch-box and switch-operating means. Fig. 3 is a sectional view taken on the line 55 3 3 of Fig. 2; and Figs. 4, 5, 6, and 7 are diagrammatic views of the circuits, illustrating the operation of the signal-lights, each view representing the same block and showing the various courses taken by the electric current 60 when the switches are operated by the passing of the trains.

In the drawings, 1 indicates the rail of any ordinary road-bed, 2 the supporting-ties therefor, and 3 the pilot of a locomotive. 65 Positioned at suitable distances along the rail is a series of switches 4, 5, the distance between the switches of the series constituting a block. Each switch comprises in its construction a box to one side of which is attached an ordinary three-way electric-light switch S, except the thumb-button is removed and in its place is secured a four-cogged wheel 9. Partially inclosing the wheel 9 is a cap 10, rotatably mounted on a 70 shaft 8, journaled in a bracket 7. The rim of the cap is provided with the ratchet or teeth 11; but said ratchet does not extend entirely around the cap, but approximately half-way the periphery thereof. The teeth 11 mesh 75 with a toothed rack 12, slidable vertically within the box and mounted in a guide-bar 13, secured to a wall or side of the box. Said guide-bar consists of a back strip having formed near each end an arm or projection 80 14, provided with an opening or aperture 15, through which the rack-bar passes. It is to be noticed that the rack-bar is not toothed its entire length, but for a portion of its length between the arms 14, and the toothed portion 85 90 is not of sufficient length to in any way interfere with the bar in its movement. The upper portion of the rack-bar 12 passes through an opening 16 in the top of the box and is secured at its end centrally to a bow-spring 17. 95

Within the cap 10 and to the side thereof is pivoted a pawl or dog 18, which engages the teeth 11 of the wheel 9 to move the cap in one direction, said pawl riding free thereover when the cap moves in the opposite direction. A spring 19 is interposed between the pawl and the rim of the cap to hold said pawl normally in contact with the wheel 9. This spring may be of any preferred form; but it

is found best in practice to have the peculiar shape shown in the drawings, of which no description is thought necessary in view of the distinctness of illustration. It may be 5 stated that the end engaging the rim is bent back upon itself to form a greater bearing-surface to increase the tension of the spring.

The ends of the bow-spring 17 are provided with elongated slots 20, through which pass 10 the headed bolts 21. These bolts are driven in and held by the cross-ties 2; but attention is directed to the fact that although said bolts hold the spring 17 against displacement they do not interfere with a longitudinal movement of the spring caused by the depression thereof, as will be hereinafter described. The bow-spring is of such size as to extend 15 slightly above the upper surface of the rail 1, and such elevation is intended to be given it 20 as to cause the wheel 9 of the switch to turn a little more than one-fourth of a revolution when the said spring is depressed. To have the turn slightly in excess of a one-fourth revolution assures a positive operation of the 25 switch. To depress the spring, suitable means are provided on the trains passing over said rails, and such means are preferably secured to the pilot of a locomotive. The means comprise a curved spring 22, hinged to 30 the pilot 3 at 23, the other end of the spring being fastened to the pilot by a bolt passing through a slot 25 in said spring. Carried by the spring is a depending roller 26, which is 35 so positioned as to contact with the spring 17 to depress the same sufficiently to operate the switch.

Stationed along the road and preferably supported by poles 27 is a feed-wire 28, connected to any suitable source of electricity. 40 This wire is of course connected to the switches 4 5. In the diagrams, *a b* indicate the points of the switch in connection with the wire 28 through wire *c* in switch 4, and *a', b',* and *c'* indicate corresponding parts in switch 5.

d d' indicate the switch-blades.

e e' and *f f'* indicate the contact-points of switch. Points *f f'* are connected by the wire *g*, and the points *e e'* are connected by 50 the wire *h*. Arranged on the wire *g* and *h* at both ends of the blocks are signal-lights *k k'*, preferably the well-known red lamps. Although not shown in the drawings, it is the intention of the invention to have the wires 55 *g h* pass through the stations on the blocks or to other points of vantage and to be provided with suitable lamps to indicate to station-masters or other officials the conditions of the block. The circuit is alternately changed by 60 the switch from the wires *g* and *h*—that is to say, when a train enters a block the switch completes a circuit through either wire *g* or wire *h* and when it passes off the block it

breaks said current or circuit. A train following will complete a circuit through the 65 wire other than the one in previous circuit, or if a train should back on the block it would complete the circuit through the same wire. This operation is thought to be fully disclosed in the diagrammatic views of the drawings, Figs. 4, 5, 6, and 7. Fig. 4 indicates the block as empty. Fig. 5 indicates that a train has passed in from left, the signal showing over line *h*. Fig. 6 shows that a train has passed out at the right and the block is 70 empty, and Fig. 7 shows that train has passed in from the left and the signals showing over the line *g*.

It is to be stated that the spring 17 is of sufficient tension to keep the rack-bar 12, or 80 "plunger," as it may be termed, normally elevated.

Having thus fully described my invention, what I claim as new, and desire to secure by Letters Patent, is—

85

1. In a device of the character described, a switch-box, a three-way switch on the side of said box, a cogged wheel on the switch, a cogged cap covering said cogged wheel, said cogged cap being held in position to allow the 90 cap to rotate, which cap when rotated in one direction works the switch, and when rotated in the other direction permits the switch to remain stationary; a spring and ratchet or cogged plunger, adjusted to operate the cap, 95 a roller attached to a portion of the train, and adjusted to operate the spring or plunger with each passage of the train.

2. In a device of the character described, a switch-box, a switch within the box, a rotary 100 member within the box, a spring-pressed pawl carried by the rotary member engaging the switch, a guide-bar arranged vertically within the box, and a plunger extending within the box held by the guide-bar, said plunger 105 imparting motion to the rotary member.

3. In a device of the character described, a switch-box, a switch within the box, a rotary member within the box, a spring-pressed pawl carried by the rotary member engaging 110 the switch, a guide-bar within the box, a perforated arm near each end of the bar, a plunger extending within the box and through the perforations of the arms, said plunger 115 imparting motion to the rotary member.

4. In a block system, suitable feed and return wires, block-signals at each end of a block, conductors for each set of signals, a switch at the end of each block for controlling the current to the conductors, comprising in its construction a smooth box, a three-point switch thereon, a cogged wheel on the switch, a cogged cap covering said cogged wheel, said cogged cap being held in position to allow the cap to rotate, which cap when 120 rotated in one direction works the switch, 125

and when rotated in the other direction permits the switch to remain stationary; a spring and ratchet or cogged plunger, adjusted to operate the cap, a roller attached to a portion 5 of the train, and adjusted to operate the spring or plunger with each passage of the train.

In testimony whereof I affix my signature, in the presence of two witnesses, this 16th day of June, 1905.

ALBERT M. MOTT.
